UNITED STATES PATENT OFFICE.

BENJAMIN M. SHANKLIN, OF SPRINGFIELD, MASSACHUSETTS.

STRIP-PUNCHING APPARATUS.

1,346,916.

Specification of Letters Patent. Patented July 20, 1920.

Application filed November 5, 1918. Serial No. 261,196.

To all whom it may concern:

Be it known that I, BENJAMIN M. SHANKLIN, a citizen of the United States of America, residing at Springfield, in the county 5 of Hampden and State of Massachusetts, have invented certain new and useful Improvements in Strip-Punching Apparatus, of which the following is a specification.

This invention relates to improvements in 10 strip punching apparatus and more particularly to apparatus which is arranged to contain and operate upon a roll of transfers or the like in continuous strip form.

One object of the invention is to provide 15 a strip punching mechanism, which is particularly designed for use in street cars and the like, and involves a segregation of all the relatively elaborate punching mechanism into one relatively small and conveniently portable casing and the grouping of 20 the relatively simple and inexpensive actuating devices for such mechanism in a stationary pedestal, together with means connecting the pedestal and casing to permit 25 convenient removal of the latter.

Another object is to provide in combination with a strip punching apparatus of the type described, a single lever to actuate the entire apparatus and means permitting the 30 removal of such lever together with a disposition of parts such that by the removal of the lever the entire mechanism is proof against actuation.

Another object of the invention is to provide 35 in an apparatus of the class described several groups of punches and improved and manually operable devices to select any one punch of each group for subsequent actuation.

40 A further object of the invention is to provide in a strip punching apparatus generally simplified and improved mechanical structure.

Other features and advantages will appear 45 in the following description and in the illustrative embodiment of the invention in the accompanying drawings, in which:

Figure 1 is an elevational view, partly in section, of an apparatus embodying the invention;

Fig. 2 is an enlarged top plan view of the apparatus, shown as removed from its supporting pedestal;

Fig. 3 is a fragmentary bottom plan view 55 of the apparatus, showing means for connecting it to its supporting pedestal;

Fig. 4 is a sectional plan view taken on the line 4—4 of Fig. 1;

Fig. 5 is an enlarged elevational view of the apparatus; with part of the casing 60 broken away to reveal interior mechanism;

Fig. 6 is a sectional plan view illustrative of a detail of the operating mechanism;

Fig. 7 is a sectional view taken on the line 7—7 of Fig. 6;

Fig. 8 is an enlarged fragmentary cross-sectional view taken on the line 8—8 of Fig. 2;

Fig. 9 is an enlarged fragmentary cross-sectional view taken on the line 9—9 of Fig. 1;

Fig. 10 is a detail elevational view of a part shown in Fig. 7;

Figs. 11 and 12 are sectional views taken on the lines 11—11 and 12—12 respectively 75 of Fig. 9;

Fig. 13 is an enlarged fragmentary cross-sectional view taken on the line 13—13 of Fig. 2;

Fig. 14 is a fragmentary sectional view 80 taken at right angles to Fig. 13; and

Fig. 15 is a fragmentary plan view of Fig. 14.

Referring to these drawings in detail: The transfer issuing and punching mechanism is contained within a casing A, which in turn is supported upon a pedestal B. Associated with the latter is a lever, preferably in the form of a foot pedal p, whereby the mechanism within casing A may be actuated 90 as will later appear in detail. When the apparatus is used, as contemplated, in street car service, two of the pedestals B will of course be employed, one at each end of the car and rather than to provide duplicate 95 mechanism of the sort contained in casing A, means are provided whereby the casing A may be conveniently removed from pedestal B and subsequently connected to another like pedestal.

For example, the lower portion of the casing A and the upper portion of pedestal B are provided with inter-engageable female and male ends 20 and 21 respectively. On the interior surface of the end 20 are 105 three angularly spaced wedge-like projections 22 (Figs. 1 and 3) which converge downwardly and restrict the open lower end of member 20. Formed on the exterior surface of member 21 are three angularly 110 spaced and similar wedge-like projections 23 (Figs. 1 and 4) which diverge upwardly

and enlarge the upper end of member 21. The spaces between the projections 22 are at least equal in width to the projections 23 so that the two ends 20 and 21 may be telescoped, when the projections 22 of the former are so located as to pass between the projections 23 of the latter. Then, by turning the end 20 relatively to the end 21 through an arc of substantially 120 degrees, 5 the wedge-like projections of the former are brought into engagement with the projections 23 of the latter to interlock the two ends. The exterior of the end 20 is threaded 10 to receive a suitable nut 24, the lower face 15 of which is adapted to engage a part of the pedestal, and, by turning nut 24, the end 20 may be raised to draw its projections 22 into intimate and binding engagement with the projections 23 and thus firmly hold the 20 pedestal B and casing A in interlocked relation. It will, therefore, be seen that the casing A is readily and conveniently removable from pedestal B and as readily and conveniently applicable to a pedestal of like construction. 25

The pedestal B, as described, is provided with a foot pedal *p* to actuate the mechanism in casing A. Such pedal is provided intermediate its ends with a pivot pin 25 (Figs. 1 and 4), which extends from each side of the pedal and the ends of which are adapted to lie in vertical slots 26 formed in two spaced lugs 27 on the pedestal. The 30 pedestal *p* fits between lugs 27 and its inner end passes through a slot 28 in the pedestal and underlies the lower end of a rod 29. Pedal *p* may be conveniently removed by lifting its outer end until pin 25 is free from slots 26, whereupon the pedal may be withdrawn. 35 Thus, the one pedal may be used with two pedestals, but more important is the fact that the pedal may be removed, whenever the attendant leaves the apparatus, for the purpose of preventing unauthorized persons from operating the apparatus and fraudulently obtaining transfers. 40

The described rod 29 is suitably mounted in pedestal B to slide vertically. A spring 50 30 acting between the top of the pedestal and a collar 31 on rod 29 tends to hold the latter in its lower position, in which a collar 32 on rod 29 abuts a ring 33 secured to the pedestal. The top of rod 29 underlies a rod 34 which is slidably mounted in casing A and extends into the hollow end 20 described. Referring now to Fig. 5, the upper end of rod 34 is pivotally connected to an arm 35 which is mounted on a shaft 36 journaled in a pair of spaced side frames C suitably supported from the bottom wall of casing A. Also mounted in frames C is a shaft 37 upon which is suitably fixed at one corner a triangular shaped arm 38. One free corner of the latter is connected by a link 39

with the described arm 35 and the other and lower corner of arm 38 is connected by a coil spring 40 with the frame C. Also fixed upon shaft 37 is a segmental gear 41 from which the transfer punching and feeding mechanism is actuated. The spring 40 tends to hold the gear 41, rod 34 and connected parts in the illustrated position, in which the lower end of link 39 abuts the bottom wall of casing A as a stop. It will readily be apparent that upon a depression of pedal *p*, the gear 41 will be turned in a counterclockwise direction and upon release of such pedal, the gear will be moved in an opposite direction and returned into the 75 illustrated position by the spring 40, the rod 29 being independently returned by spring 30.

The described frames C support a plate 42 (Fig. 8) which is provided with a longitudinal channel 43 through which the strip to be punched, as *s*, (Fig. 5) is passed. The strip *s* is conveniently provided in roll form and the roll of strip is supported on an arbor 44 mounted in the side frames C. 80 From the arbor 44, strip *s* passes through the passage 43 and emerges from the right hand end of the casing A, as indicated. The strip *s* may be drawn through passage 43 by any suitable means and the present invention is not concerned with the strip feeding means. It is understood that a suitable type of strip feeding means may be provided in casing A and may be operated from the gear 41 by suitable connections exemplified in part by the gear 45, but, inasmuch as a knowledge of the strip feeding means is unnecessary to an understanding of the present invention, detailed illustration and description of such means will be omitted. 90

Upon the described plate 42 is a plate 46 in which are mounted a plurality of groups of punches, among which are a group of destination punches 47 (four of which are shown in Fig. 8); a group of three punches 48 (Fig. 9) comprising a punch for each of the quarter hour printed designations on strip *s*; a group of two punches 49 (Fig. 9) one of which is adapted to punch the "A. M." and the other the "P. M." printed designations on the transfer strip *s*; and a group of two punches 50 (Fig. 13) one of which is adapted to punch the "In bound" and the other the "Out bound" printed designations on the transfer strip *s*. Other groups of punches may be provided as desired, or as is necessary to suit the particular requirements of various types of transfer strips. The present groups of punches are described merely because it will be necessary to later refer to them for an understanding of other and novel features to be later described. 100

All of the punches are of similar construction and a description of one punch, 110

as 47, will suffice for all. As shown in Fig. 8, the punch 47 is mounted to slide vertically in plate 46 and is normally held in elevated position, wherein its lower end is flush 5 with the bottom of plate 46, by a spring 51 which tends to lift the punch by engagement with a collar 52 thereon, the collar of this, as well as those of all the other punches, being engageable with a thin cover plate 53 10 on plate 46 as a stop. Each punch is capable of being depressed by means to be described and when depressed passes through the strip *s* in passage 43 and into a hole 54 in plate 42, the punched out portions of the 15 strip falling into a suitable receptacle, as a pan 55 secured to the under side of plate 42 as shown.

The punch depressing devices for each of the several groups of punches are all carried 20 on a frame D, which is compressible by means actuated by the described gear 41. Thus, to each side of frame D is fixed a pair of spaced rods 56 (one pair of which appears in Fig. 5) and each pair of such 25 rods pass through and are slidably mounted in an outwardly projecting part 57 of frame C (see also Fig. 8). Between such part and frame D are springs 58 which tend to hold the frame in elevated position. The 30 lower ends of each pair of rods 56 are connected by a cross-bar 59. Mounted in frames C is a shaft 60 which projects from the sides of the frames and bears a cam 61 (see also Figs. 6 and 7). Intermediate 35 the ends of shaft 60 and loosely mounted thereon is a pinion 62 which meshes with the described segmental gear 41. Fixed to pinion 62 is a hollow disk 63 to which is pivoted a pawl 64. Within disk 63 and fixed 40 to shaft 60 is a ratchet 65 having a single tooth, as shown in Fig. 7, to receive the pawl 64. Obviously, as gear 41 is moved in a counter clockwise direction, the pinion 62 and pawl carrying disk 63 will be turned in 45 a clockwise direction, so that pawl 64, having been previously engaged with the tooth of ratchet 65, will turn the latter and thus shaft 60 and cams 61 in a clockwise direction. On a reverse movement of gear 41, 50 however, the ratchet 65 will not be turned and such movement of the gear 41 may be made to operate other mechanism, as the strip feeding mechanism, through the gear 45 and other devices with which this invention 55 is not concerned. The ratio between gear 41 and pinion 62 and the extent of oscillation imparted to gear 41 is so designed as to effect one complete revolution of pinion 62. Thus, cam 61 will be turned through 60 one complete cycle to lower frame D and thereafter permit it to return into the illustrated position under the force of springs 58.

The punch actuating devices carried by frame D are of various forms, depending 65 upon the group of punches which they con-

troil and more particularly upon the frequency with which they require to be used. Thus, for the destination punches the means shown in Fig. 8 may be advantageously employed. For each punch 47 of the destination group there is provided a bell crank lever 67 pivoted at 68 to frame D. To one arm of lever 67 (the upper) is pivotally connected a bar 69 which is slidably mounted in frame D and extends upwardly above the latter. The other arm of lever 67 is adapted to overlie its punch 47 when the bar 69 is depressed. Thus, as shown in Fig. 8, the lever 67 is movable into the position indicated by dotted lines, which position is such 70 that the lower arm of the lever will engage and depress punch 47 when frame D is lowered by the mechanism already described. Each bar 69 is provided with a shoulder 70, which when the bar is depressed is engaged 75 by a latch 71 pivotally mounted at 72, whereby the bar 69 may be held in depressed position.

The present invention is not particularly concerned with the punch selectors or actuators of the destination group and the above description is given merely to enable a better understanding of certain desirable details of structure associated with this group of punches, as will appear below. Actually, 90 means are provided to interlock all the latches 71 to the end that a depression of any one blade will restore all other previously outlined in my copending application 95 Serial No. 195,311 filed October 8, 1917. Detailed description and illustration of such interlocking means is however, not necessary to an understanding of this invention and is accordingly omitted. 100

Heretofore, the upper ends of blades 69 have protruded upwardly through the outer casing A of the apparatus and have been provided with buttons or finger pieces to permit convenient depression of the bar. 110 Since the bars 69 rise and fall with frame D, by reason of the engagement of the latter with shoulders 73 on bars 69, it has been necessary to space the buttons from the upper face of casing A by a sufficient distance to permit this movement. Such arrangement is not only awkward in appearance, but the buttons must be placed on and fixed to the tops of the bars after the outer casing has been applied and they are not 115 readily removable.

According to this invention, the bars 69 do not protrude from the casing A, but terminate within the latter. Springs 74, coiled around bars 69, act between the top of frame 125 D and collars 75 on the upper ends of the bars to force the latter upwardly until the shoulders 73 abut frame D. Above frame D, and supported in parallel relation therewith by two laterally spaced standards 76 at 130

tached to the described elements 57 (as shown in Figs. 5 and 8), is a plate 77. The latter has a plurality of holes therein through which the tops of bars 69 protrude and in such holes are slidably received the hollow sleeve like lower ends 78 of buttons 79. The buttons 79 are in turn slidable vertically in two contiguous plates 80 and 81 which are removably secured in and close 5 the upper wall of casing A. The intersection of the elements 78 and 79 affords an external flange 82 and an interior shoulder 83. The shoulders 83 rest upon the upper ends of bars 69 and the flanges 82 abut the under 10 side of plate 80.

As shown in Fig. 8, the plates 80 and 81 fit within a recess in the upper face of casing A, the lower plate 80 resting upon a flange 84 of the casing and being secured thereto 15 by screws 85, (see Fig. 2). The upper plate, which will hereinafter be termed the name plate since, as shown in Fig. 2, it bears printed designations for each of the buttons 79, rests upon plate 80 and its outer face lies 20 flush with the outer top face of casing A. Screws 86 threaded into casing A have their heads arranged to overlie plate 81. A portion of the heads of screws 86 are cut away, as at 87, so that the screws may be turned 25 slightly to release plate 81 and allow it to be quickly removed and another name plate substituted for it, if desired.

The punch actuators or selectors for the punches 48 and 49 are of a different type 30 as will now be described with particular reference to Figs. 9, 10, 11 and 12. The frame D has rotatably mounted therein a shaft 88, upon which are actuators for the punches 49 and other actuators for the punches 48. 35 Thus, the shaft 88 has near one end three pins 89 which extend diametrically therethrough and project equidistantly from opposite sides of the shaft. The pins 89 are located axially on the latter in the vertical 40 planes of their respective punches 48, as shown, in Fig. 9. As shown in Fig. 12, the pins 89 are angularly spaced from one another on shaft 88 by angles of forty-five degrees. By turning shaft 88, each pin 89 45 may be made to overlie its punch 48 twice in each revolution and at such positions no other pin 89 will overlie any other punch 48. Also on shaft 88 are two axially spaced and oppositely arranged semi-circular flanges 90, 50 one arranged to overlie one punch 49 and the other to overlie the other punch 49. The arrangement is such that one or the other of punches 49 will always be actuated irrespective of the angular position of shaft 88. On 55 one end of the latter is fixed a disk 91, the inner face of which is engaged by a spring pressed detent 92 slidable in a bar 93 secured to the frame D. In back of shaft 88, there is another shaft (not shown) which has on 60 one end (that opposite from disk 91) a disk 65

94 which is engaged by a similar detent 95 mounted in bar 93. Such second shaft may be similar in construction to shaft 88 and the exact detailed construction of either of these shafts is immaterial to the present invention. 70

The present invention is concerned more particularly with means for turning the shaft 88 and any other like shaft which carries punch actuators and which is itself 75 depressible. Since the means for turning shaft 88 must for convenience be mounted in the stationary outer casing A, provision must be made to permit the rising and falling of shaft 88 with relation to the casing A. 80 This I provide for by the following means which constitute one feature of the invention. Thus a knurled disk 96 is rotatably mounted on an inwardly projecting stud 97 of a bracket 98 secured to the outer side face 85 of casing A and the latter and bracket serve also to hold the disk 96 against axial movement. Fixed on one face of the disk 91 and projecting toward the adjacent face of disk 96 are a pair of pins 99 which are equidistantly located from the center of shaft 88 and arranged diametrically opposite one another. Fixed on the inner face of disk 96 and projecting toward the adjacent face of disk 91 are a pair of similarly arranged pins 99 90 100. In the assembling of the machine, disk 96 is turned until its pins 99 are spaced from pins 100 by angles of ninety degrees. A loose plate 101 (see Fig. 10) is provided with four radial and right angularly arranged 100 slots 102. As indicated in Fig. 8, the pins 100 extend in one direction into two of the slots 102 and the pins 99 extend in an opposite direction into the other two slots. The arrangement is such that disk 91 can move 105 downwardly from the illustrated position without disengaging pins 99 from slots 102 and so that shaft 88 may be turned by disk 96 despite the rise and fall of the former. Two small pins 103 are provided on disk 101 110 to loosely engage the inner face of disk 96 for the purpose of spacing disk 101 therefrom. As indicated, in Fig. 8, similar means are provided on the other side face of the machine to operate another shaft similar to 115 shaft 88, such other shaft being operable by a knurled disk 104 and associated devices similar to those just described.

Another group of punches, such as the punches 105 (Fig. 14) may be selected for actuation on depression of frame D by means which are not accessible from without the casing A. Thus, a plate 106 slidably mounted in frame D to permit its removal, contains a plurality of holes 107, one 120 overlying each punch 105. A pin 108 is insertible in any of the holes 107 to select the desired punch 105 and the head 109 of pin 108 abuts frame D, as shown, to prevent axial movement of the pin. Thus, on de- 125 130

pression of frame D, the punch 105 which underlies pin 108 will be actuated by the latter.

Still another group of punches,—the two punches 50 (Fig. 13),—require to be operated with greater frequency and, therefore, by means which are necessarily accessible from outside the casing A. The punches 50, as at present contemplated, control the "In bound" and "Out bound" printed designations on strip s. Obviously, they may be used for other purposes and the mechanism, for selecting and actuating these punches, is designed for any group of two punches which require that either one or the other of the two punches be operated. The present arrangement is characterized in that the selection of one punch automatically restores the selector for the other punch and this result is accomplished by improved means as will now be described.

Referring to Fig. 13, a single punch actuator 110 is provided which, as shown, in Fig. 14, protrudes through a suitable slot in frame D and depends into proximity with the horizontal plane in which the upper ends of punches 50 are disposed. The member 110 has an upper cross-bar portion 111 which is supported by, and mounted to slide horizontally with respect to, a bracket 112 secured to frame D. Studs 113 secured to the bracket 112 pass through horizontal slots 114 in the cross-bar 111 to permit the sliding movement described. The means, for sliding member 111 and thus setting member 110 or selecting the desired punch 50, must needs be carried by the stationary frame, as the described plate 77, for example. Thus, a plate 115 is pivoted by the stud 116 to frame 77 and is so mounted as to swing in a vertical plane parallel and closely adjacent to that in which the cross-bar 111 is disposed. On plate 115 and below the pivot stud 116 is an outwardly projecting pin 117 which lies in a vertical slot 118 in the described cross-bar 111. Such pin and slot connections permit rise and fall of the frame D relatively to the stationary frame 77. Above the pivot stud 116 and substantially diametrically opposite from pin 117, there is provided on plate 115 a pin 119 which extends oppositely from pin 117 and overlies the upper face of plate 77. Mounted to slide vertically in the latter and vertically in line with the center of stud 116 is a spring pressed detent 120. The upper end of the latter is disposed intermediate the two extreme positions of pin 119 and as shown engages the pin to releasably hold it in one or the other of such positions. The upper end of detent 120 being pointed, the pin 119 may cam it downwardly to permit swinging of plate 115, but the upward pressure of the pointed detent on pin 119 forces it to assume one or the other of its extreme

positions. There remains only to provide means accessible from outside casing A to rock the plate 115 and this is accomplished by buttons 121, similar to and interchangeable with, the buttons 79 described. The buttons 121 are slidable in plates 80 and 81 and have lower and integral sleeve-like portions 122 which are slidable in plate 77. Each of the hollow portions 122 is arranged to receive a prong-like and generally upwardly extending portion 123 of plate 115. The flange 124, at the intersection of the buttons 121 with the portions 122, abut either the upper face of plate 77 or the under face of plate 80, accordingly as the buttons are in elevated or depressed position. It will be readily seen that a depression of the button 121, which is in elevated position, will rock plate 115 in a clockwise direction (Fig. 13) and slide the part 110 to the left so that the latter overlies the left hand punch 50. Such movement of plate 115 will necessarily elevate button 121 so that it may subsequently be depressed to shift the punch actuator 110 back into the illustrated position.

In operation, the operator first selects the appropriate punch of each of the several groups. Thus, he depresses one of the several buttons 79, one of the buttons 121, and turns the disk 96 or disk 104 or both, as necessary. The pin 108, of course, is also fitted into the appropriate hole 107, although this pin is used to control a group of punches which requires a change only at infrequent intervals. It may not always be, and frequently is not, necessary to make all the selections described. The selections having been made, the operator then depresses pedal p, which as already described, results in a depression of frame D and thus an actuation of the several selected punches and a perforation of the strip s at a plurality of predetermined points. The strip s may be fed through the machine in any suitable manner, in so far as this invention is concerned, as by hand if desired or automatically as disclosed in the above-mentioned co-pending application.

In the practical use of the punching apparatus, the operator is provided with only one casing A and this casing is shifted from one end of the car to the other and temporarily connected to a supporting pedestal B. The pedal p is likewise shiftable from pedestal to pedestal in a like manner and, more important still, it is readily removable whenever the operator leaves the apparatus for the purpose of effectually preventing the operation of the apparatus during the absence of the operator. The means for permitting the removal of the apparatus from the pedestal and the removal of the actuating pedal therefrom constitute important features of the invention.

The means for moving the shaft 88, and thereby selecting various punches, is considered an important feature in an apparatus of the present character for the reason that it permits connection between stationary and reciprocable parts by mechanism of the simplest sort. The construction of the selector and punch actuating mechanism for the punches 50 is also considered important for 10 a like reason and for the reason that such mechanism is simple, inexpensive to construct, easy to assemble and withal efficient and convenient for its intended purpose. The provision of the removable name plate 15 81 and the readily removable and interchangeable buttons 79 and 121 constitute important features of the invention. The buttons or finger pieces may be standardized and manufactured in large quantities at 20 low cost. The buttons are devoid of all markings, these being applied to the plate 81 which is interchangeable with other similar plates bearing different markings. This feature of the invention makes the apparatus 25 practical and commercially satisfactory for street railway operation for the same apparatus may be used on different lines and different systems without requiring anything other than the substitution of a different name plate and the use of a differently printed transfer strip 8.

The invention has been disclosed herein, in an embodiment at present preferred, for 35 illustrative purposes, but the scope of the invention is defined by the appended claims rather than by the foregoing description.

What I claim is,—

1. In a strip punching apparatus, two 40 depressible punches, a frame depressible toward said punches, a punch actuating member carried by said frame and slidable therein from a position wherein it is effective to engage one of said punches to a position wherein it is effective to engage the other of said punches on depression of said frame, a stationary frame, and means carried by the latter to shift said member from one position to the other, said means including connections to permit relative movement between said frames.

2. In a strip punching apparatus, two de- 45 pressible punches, a frame depressible toward said punches, a punch actuating member carried by said frame and slidable therein from a position wherein it is effective to engage one of said punches to a position wherein it is effective to engage the other of said punches on depression of said frame, a stationary frame, means carried by the latter to shift said member from one position to the other, said means including connections to permit relative movement between said frames, and means to releasably hold said member in each of said positions.

3. In a strip punching apparatus, two de-

pressible punches, a frame depressible toward said punches, a punch actuating member carried by said frame and slidable therein from a position wherein it is effective to engage one of said punches to a position 70 wherein it is effective to engage the other of said punches on depression of said frame, a stationary frame, a teeterable lever carried by said second frame and connected to said member to shift the same from one position 75 to the other and permit relative movement between said frames, and a device associated with said lever to yieldingly hold it in each of its extreme positions and prevent it from coming to rest in an intermediate position. 80

4. In a strip punching apparatus, two de- 85 pressible punches, a frame depressible toward said punches, a punch actuating member carried by said frame and slidable therein from a position wherein it is effective to engage one of said punches to a position wherein it is effective to engage the other of said punches on depression of said frame, a stationary frame, a teeterable lever carried by said second frame and connected to said 90 member to shift the same from one position to the other and permit relative movement between said frames, and a device associated with said lever to yieldingly hold it in each of its extreme positions and prevent it from 95 coming to rest in an intermediate position, said lever having an arm on each side of its pivotal axis, and a finger piece carried by each arm whereby an actuation of one arm in one direction will move the other arm 100 in the opposite direction for convenient operation subsequently in the first-named direction.

5. In a strip punching apparatus, an in- 105 closing casing, a depressible frame therein, a punch actuating member slidable on said frame from one position to another, a punch arranged to be engaged by said member in each of its two positions, a teeterable lever, means relatively stationary with relation 110 to said frame upon which means said lever is pivoted, a pin on said lever, a slot provided in said member to receive said pin, means tending to hold said member in and force it to assume one or the other of said 115 positions, arms on said lever, one on each side of its pivot, and depressible buttons slidable in said casing and having hollow inner ends to loosely receive said arms.

6. In a strip punching apparatus, an in- 120 closing casing having an opening in its upper face, a stationary member within the casing, a plurality of depressible punches in said member, a frame in said casing and movable between said member and said face, 125 punch actuating devices carried by said frame and movable to and from positions in which they are effective to engage said punches on movement of said frame toward said member, depressible members associated 130

with said devices to move the latter, each of said members terminating entirely within, but with an end closely adjacent said face, a closure plate for the latter and removably secured to said casing, and a plurality of buttons loosely resting upon said ends and 5 slideable in said closure plate.

7. In a strip punching apparatus, an inclosing casing having an opening in its upper face, a stationary member within the casing, a plurality of depressible punches in said member, a frame in said casing and movable between said member and said face, punch actuating devices carried by said 10 frame and movable to and from positions in which they are effective to engage said punches on movement of said frame toward said member, depressible members associated with said devices to move the latter, each of 15 said members terminating entirely within, but with an end closely adjacent said face, a closure plate for the latter and removably secured to said casing, a plurality of buttons loosely resting upon said ends and 20 slideable in said closure plate, and a second plate superimposed on the closure plate and readily removable independently of the latter, said second plate adapted to bear appropriate designations for said buttons.

25 8. In a strip punching apparatus, an outer casing having an opening in its upper face, a stationary plate within the casing and below said face, a depressible frame within the casing and below said plate, a plurality of depressible members carried by 30 said frame, openings provided in said plate through which the upper ends of said members protrude, buttons having recessed lower

ends to loosely receive and rest upon said ends of the members, each of said lower ends 40 fitting in said openings to hold the buttons properly positioned and in upright relation, and a removable closure plate for the first-named opening and having openings to receive the upper ends of said buttons. 45

9. In a strip punching apparatus, an outer inclosing casing, a punch-carrying member therein, a frame within the casing and movable toward and away from said member, a plurality of punch actuators, a support for the latter rotatable in said 50 frame to bring one or more of said actuators into position to actuate a punch on depression of said frame, a rotatable device on the casing, and means connecting said device 55 and rotary support, whereby the latter may be moved from without the casing and may move relatively thereto on depression of said frame.

10. In a strip punching apparatus, an outer inclosing casing, a punch carrying member therein, a frame within the casing and movable toward and away from said member, a plurality of punch actuators, a support for the latter rotatable in said 60 frame to bring one or more of said actuators into position to actuate a punch on depression of said frame, a rotatable device on the casing, and means in the nature of a universal joint connecting said device and 65 rotary support, whereby the latter may be moved from without the casing and may move relatively thereto on depression of said frame. 70
